UNITED STATES PATENT OFFICE.

VICTOR MAY, OF CHICAGO, ILLINOIS.

RESILIENT HEEL.

1,112,635.

Specification of Letters Patent.

Patented Oct. 6, 1914.

Application filed October 2, 1913. Serial No. 792,932.

To all whom it may concern:

Be it known that I, VICTOR MAY, a citizen of the United States, and a resident of the city of Chicago, county of Cook, and State of Illinois, have invented certain new and useful Improvements in Resilient Heels, of which the following is a specification.

My invention relates to improvements in resilient heels and has for its object the provision of a construction of this character which is of simple construction, efficient in use and capable of being readily adjusted to compensate for wear and renewal when worn out.

15 The invention consists in the combinations and arrangements of parts hereinafter described and claimed.

The invention will be best understood by reference to the accompanying drawing forming a part of this specification, and in which,

Figure 1 is a longitudinal section taken through a heel embodying my invention, Fig. 2, a section taken on line $x-x$ of Fig. 1, Fig. 3, a perspective view of a metallic socket-member employed in the construction, Fig. 4, a longitudinal section of a heel illustrating the same when adjusted to compensate for wear, and Fig. 5, a section 25 taken at right angles to Fig. 4.

The preferred form of construction as illustrated in the drawing comprises a cylindrical metallic socket-member 1 which is adapted to be secured within a suitable 35 socket provided in the heel 2 of a boot or shoe. An air passage 3 leads from the inner side of the socket in the heel to the interior of the boot or shoe and permits free access of air to prevent the formation of a vacuum 40 therein which would interfere with the resiliency of the construction. The sides of the socket-member 1 are provided with perforations 4 and the inner end of said socket-member is provided with a large central 45 opening 5 surrounded by a supporting flange as shown. Socket-member 1 is secured in position in the heel 2 by means of tangs 6 which are formed in the sides of said socket-member and which are forced outwardly 50 into the heel after said socket member is placed in position as indicated in Fig. 5. At its outer edge socket-member 1 is provided with an outwardly extending lip or flange 7 fitting against the bottom of the 55 heel which serves to reinforce the construc-

tion and add a finished appearance thereto. A cylindrical rubber pad 8 is fitted snugly within socket-member 1 to rest upon the flange surrounding opening 5 and is frictionally held therein in position to project slightly from the heel 2 as indicated in Fig. 1. The perforations 4 in the sides of socket-member 1 assist in retaining pad 8 in position and also increase the resiliency of said pad due to the fact that the rubber is free to expand outwardly into openings 4 as will be readily understood. Central opening 5 also adds to the resiliency of the pad by permitting expansion thereof into said opening. By making the pad and socket-member cylindrical in form, said pad may be removed from said socket-member and adjusted angularly therein so as to compensate for unevenness of wear. When the protruding portion of the pad has been materially worn so as to interfere with its efficiency, a washer 9 is inserted in socket-member 1 under said pad which thus serves to cause said pad to protrude from said socket member sufficiently to perform its functions. Upon further wear additional washers or a washer of increased thickness, may be added to compensate for the wear. The specific form of construction illustrated is simple and capable of economical manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. The combination with a heel having a socket therein, of a metallic socket-member 100 having an opening in its top surrounded by a supporting flange to form an air space and secured in said socket; and a removable resilient pad fitting said socket-member, substantially as described.

2. The combination with a heel having a socket therein, of a metallic socket-member provided with inwardly exposed perforations in its sides secured in said socket; and a removable resilient pad fitting said socket- 110

member and arranged to engage said perforations, substantially as described.

3. The combination with a heel having a socket therein, of a metallic socket-member provided with inwardly exposed perforations in its sides and an opening in its bottom surrounded by a supporting flange to form an air space and secured in said socket; and a removable resilient pad fitting said socket-member, substantially as described.

4. The combination with a heel having a socket therein, of a metallic socket-member secured in said socket, there being an air passage leading from the inner end of said socket to an outside air supply and arranged to permit the passage of air thereto or

therefrom; and a resilient pad in said socket, substantially as described.

5. The combination with a heel having a socket therein, of a metallic socket member secured in said socket, there being an air passage leading from the inner end of said socket through the heel to the interior of the shoe; and a resilient pad in said socket member, substantially as described.

In testimony whereof I have signed my name to this specification in the presence of two subscribing witnesses.

VICTOR MAY.
